UNITED STATES PATENT OFFICE.

GEORGE HENRY WHEARY, OF RACINE, WISCONSIN, ASSIGNOR TO WHEARY TRUNK COMPANY, OF RACINE, WISCONSIN, A CORPORATION OF WISCONSIN.

TRUNK FITTING.

Application filed June 18, 1925. Serial No. 37,980.

It has been found that at times when a trunk receives a severe blow on one corner the sections are twisted with respect to each other sufficiently to release the section locking means and this invention has as an object to provide an improved fitting which will prevent the accidental opening of the sections irrespective of the stresses placed thereon.

10 Another object of this invention resides in the provision of an improved trunk fitting having a hasp member adapted to be spring held in either inoperative or operative position.

15 This invention has as a further object to provide a trunk fitting of the character described in which a slideable locking bolt cooperates with and is controlled by a hasp member whereby twisting of one trunk section with respect to the other is prevented.

20 And a still further object of this invention resides in the provision of an improved trunk fitting of the character described which will be of strong but neat construction and 25 in which the locking bolt and spring means are concealed.

With the above and other objects in view which will appear as the description proceeds, my invention resides in the novel construction, combination and arrangement of parts substantially as hereinafter described and more particularly defined by the appended claims, it being understood that such changes in the precise embodiment of the 35 herein disclosed invention may be made as come within the scope of the claims.

In the accompanying drawing, I have illustrated one complete example of the physical embodiment of my invention constructed according to the best mode I have so far devised for the practical application 40 of the principles thereof, and in which:

45 Figure 1 is a fragmentary, perspective view of the lower bottom portion of a wardrobe trunk illustrating one application of my improved fitting;

Figure 2 is an enlarged view in elevation of the improved fitting;

50 Figure 3 is a view, partly in elevation and partly in section, taken through Figure 2 on the plane of the line 3-3;

Figure 4 is a transverse, sectional view taken through Figure 3 on the plane of the line 4-4, and

55 Figure 5 is a view similar to Figure 4

taken through Figure 2 on the plane of the line 5-5.

In the accompanying drawing, in which like numerals designate like parts throughout the several views, my improved trunk fitting is illustrated as applied to a trunk of the "Wardrobe" type, in which two sections 5 and 6 are hingedly connected along one marginal side with their bottoms disposed on different planes. The bottom of the section having its bottom on the lower-most plane has a member 7 extended from its bottom to fill the space beneath the bottom of the other section in the manner illustrated and over which said other section moves to closed position. The extension member 7 and the lower marginal portions of the section movable thereover are provided with suitable interlocking valance and corner members to insure the proper connection between the parts when the trunk is closed and the improved trunk fitting, forming this invention, is secured to the adjacent side panels 8 and 9 of the section 6 and extension member 7, respectively.

This improved trunk fitting is preferably stamped or formed from bendable sheet material and includes a plate 10 which is secured to the panel 8 with its lowermost edge in register with the line of break 11 between the section 6 and the extension 7. The medial portion of the plate is struck outwardly to form an enlargement 12 to which the upper or inner end of a hasp 13 is pivoted, in the manner hereinafter described.

The hasp 13 is channeled and of a shape approximately that of the enlargement 12, to form in appearance a continuation thereof, and the upper end of its outer face extends beyond its sides and is bent inwardly, as best shown in Figure 3, to pivotally receive a pintle rod 14 extended across the sides of the enlargement 12. The extended end of the hasp outer face is shaped to form a cam 15 which extends beyond the pintle 14 in the manner best illustrated in Figure 3 and against which a spring 33, to be later described, works. Secured to the panel 9 of the extension member 7 with its upper-most edge in register with the line of break 11 and with the plate 10 to form a continuation thereof when the trunk sections are closed, is a plate 16, the medial portion of which is longitudinally struck outwardly to form an enlargement 17; over which the hasp 13 fits 110

when in functioning position, and a bolt recess or receiver 18 into which a bolt 19, to be later described, is slidable.

The bolt 19 is carried by that portion of the fitting secured to the panel 8 and is mounted for longitudinal movement in the enlargement 12 by a guide 20 in line with the enlargement 12 and struck outwardly from the plate 10 at its lower end extended beyond the enlargement. The movement of the bolt is controlled by the closed end or yoke 21 of a link 22 which is pivoted in an eye or bearing 23 fixed to the upper end of the bolt, the ends of the yoke passing through elongated slots 24 in the sides of the enlargement 12 and an enlargement 25 formed in the medial portion of a cap member 26 forming an extension of the plate 10. The sides or arms 27 of the link 22 pass along the enlargement 12 and the hasp 13 and have their ends turned inwardly through openings 28 in the sides of the hasp, the inturned ends of the links being swedged or enlarged, as at 29, to prevent accidental dislodgement.

A locking lug 30 extends inwardly from the free end of the hasp and is engageable in a recess or opening 31 in the wall of the locking recess 18 at a point beneath the lowermost point of travel of the bolt and in an opening or recess 32 in the panel 9. The hasp and bolt are yieldably held in operative or locking position by the spring 33 which is fixed, as at 34, to the guide member 20 to cause its free end to bear against the cam portion 15 of the hasp and exert its force to hold the hasp member and bolt in functioning position. While the spring 33 may function to secure the hasp and bolt in inoperative position, a second spring 35 may be employed for this purpose which is secured in the cap member 26, as at 36, and has its free end curved, as at 37, to engage over the closed end 21 of the link 22 when in its upper-most limit of movement, as illustrated by dotted lines in Figure 3.

The cap member and plates 10 and 16 are secured to their respective panels by rivets or other means 38 and the plate 10 and cap member are connected by a tongue 39 extended from the enlargement 25 thereof and secured to the enlargement 12 by a rivet 40. The extreme lower or outer end of the hasp is preferably curved outwardly to facilitate the engagement thereunder of a finger to move the same to inoperative position and the various parts are protected against side blows by beads or ribs 42 formed in the plates 10, 16 and cap 26.

As before described, the hasp member is held in inoperative position by the spring 35 so that the bolt 19 will not interfere with the opening and closing of the trunk sections, and when it is desired to fasten the section the hasp 13 is swung downwardly on its pivot disengaging spring 35 from the

closed end of the link and engaging the bolt in the recess 18. As the hasp and bolt approach their functioning position, the spring 33 engages behind the cam 15 to yieldably retain the same against accidental movement. A plate 43 closes the rear of the plate 10 and cap member 16 and a plate 44 closes the rear side of the plate 16, the plates 43 and 44 forming the rear sides of the bolt guide and the receiving recess, respectively.

I claim:

1. In a device of the character described, the combination with two members adapted to be releasably held in closed position, of a hasp carried by one member and engageable with the other to prevent longitudinal movement between the members; means slidably operated by the hasps to prevent transverse movement between the members, and means positioned upon each member and adapted to fall in alignment when the sections are in closed position to protect the movable elements thereof.

2. In a device of the character described, the combination with two members adapted to be secured in interlocked relation, of a bolt slidably carried by one member and engageable in a recess in the other to secure the members in interlocked relation, a hasp hingedly connected with the first member and adapted to be swung into contact with the other, link means connecting the hasp and bolt whereby their movements are co-ordinated, and channels formed upon each of said members and adapted to fall in alignment when the members are in closed position to receive the link means when the device is in an operative position.

3. In a device of the character described, the combination with two members adapted to be secured in interlocked relation, of a bolt slidably carried by one member and engageable in a recess in the other to secure the members in interlocked relation, a hasp hingedly connected with the first member and adapted to be swung into contact with the other, link means connecting the hasp and bolt whereby their movements are co-ordinated, and channels formed in one of said members to receive therein the link means when the device is in an operative position.

4. A trunk fitting, comprising a plate, a bolt slidably mounted on the plate, a hasp member, means pivotally connecting the inner end of the hasp member with the outer end of the plate whereby the hasp may be swung to and from operative position, a connection between the hasp and bolt whereby the hasp and bolt are simultaneously moved to and from fastening position, fastening means carried by said hasp, and a keeper having provision for receiving the hasp fastening means and bolt.

5. A trunk fitting, comprising a plate hav-

- ing a medial enlargement thereon, a hasp member hingedly mounted from the plate, a bolt slidably mounted in the enlargement of the plate and adapted to be moved to project its outer end therebeyond, a second plate having an enlargement thereon in approximate alignment with the enlargement of the first plate, said enlargement forming a bolt receiving recess adapted to be aligned with the bolt, and a lug carried by said hasp member and adapted to engage in a recess in said second plate enlargement.
6. In a device of the character described, the combination with two members adapted to be secured in locked relation, of a hasp pivotally carried by one member and engageable with the other, a spring operating on the hasp to yieldably retain the same in position engaging the other member, and a second spring remote from the first spring and operable to yieldably retain the hasp in a position free of said other member.
7. In a device of the character described, the combination with two members adapted to be secured in locked relation, of a hasp hingedly carried by one member and engageable with the other, a link slidably connected with the member mounting the hasp and having its end pivotally connected with the hasp, and a spring engageable with the inner end of said link to yieldably secure the hasp in an inoperative position free of said other members.
8. In a device of the character described, the combination with two members adapted to be secured in locked relation, of a hasp hingedly carried by one member and engageable with the other, a link slidably connected with the member mounting the hasp and having its end pivotally connected with the hasp, a spring engageable with the inner end of said link to yieldably secure the hasp in an inoperative position free of said other member, and means engageable with the hasp proper to releasably retain the same in operative position.

In testimony whereof I affix my signature.
GEORGE HENRY WHEARY.
